(57) **ABSTRACT**

A power rack assembly attachment having at least one support member that removably attaches to a vertical post in a power rack assembly or similar exercise equipment or machine and is connected to a parallel vertical support post that can receive a support hook for barbells. The power rack assembly attachment provides the ability to extend vertical support for support hooks closer to the user than the standard vertical posts in a power rack assembly.

EXERCISE POWER RACK ASSEMBLY
ATTACHMENT

FIELD OF THE INVENTION

This invention relates in general to exercise equipment and more specifically an attachment for exercise power racks and other similar exercise equipment.

SUMMARY OF THE INVENTION

The primary object of the present invention is to provide a device to assist individuals who lift weights using a power rack assembly and other similar exercise equipment. The present invention allows an individual to create additional support members to a power rack assembly and other similar exercise equipment in order to provide vertical column support that is internal to the power rack assembly's existing vertical column support.

Power rack assemblies are commonly comprised of vertical columns having a rectangular frame made of steel comprised of pairs of front and rear vertical uprights or corner posts, usually also rectangular, connected together at their upper and lower ends to form a rigid open frame. Each vertical post has spaced apart and aligned apertures or through-holes into which horizontal spotter arms or barbell support hooks may be adjustably secured. To utilize the power rack assembly, support hooks are inserted into the apertures of the vertical posts at a height that would be just below the shoulders of a user. The user then places a barbell to be supported by the support hooks and position the barbell across the user's shoulders. The user then places each of his or her hands to be at a comfortable position along the length of the barbell and then lift the barbell off of the support hooks.

Certain lifters require the support hooks to be in a position closer to their body in order to provide a more comfortable position for their hands along the length of the barbell. Further, such positioning of the support hooks provides a more effective positioning of a user's hands for certain users, specifically for users who have a wide shoulder width.

The present invention discloses a power rack assembly attachment comprising a vertical support for use with a power rack assembly post and a parallel support member that receive and support barbell support hooks. Although the attachment may be used with a power rack assembly, it may be used with any similar exercise equipment.

It is an object of the invention to provide such an apparatus which can be attached to the vertical post of a power rack assembly.

It is another object of the present invention to provide a stable support for the barbell hooks and weight of a barbell.

BRIEF DESCRIPTION OF THE DRAWINGS

FIG. 1 is a perspective view showing a power rack assembly in broken lines wherein the present invention has been removably attached to two vertical posts of the power rack assembly.

FIG. 2 is a perspective view showing a power rack assembly wherein the present invention has been removably attached to two vertical posts of the power rack assembly.

FIG. 3 is a perspective view showing a section of two vertical posts of a power rack assembly wherein the present invention has been removably attached to such sections of the two vertical posts,

2

FIG. 4 is a perspective view showing the present invention.

FIG. 5 is a top view showing the present invention.

FIG. 6 is a perspective view showing the present invention.

FIG. 7 is a front view showing the present invention.

FIG. 8 is a back view showing the present invention.

FIG. 9 is a bottom view showing an embodiment of the present invention.

FIG. 10 is a perspective view showing an embodiment of the present invention.

FIG. 11 is a side view showing an embodiment of the present invention.

FIG. 12 is a front view showing an embodiment of the present invention.

DESCRIPTION OF THE INVENTION

The present invention is comprised of at least one support member that removably attaches to a vertical post in a power rack assembly or similar exercise equipment or machine and is connected to a parallel vertical support post that can receive a support hook for barbells. The present invention provides the ability to extend vertical support for support hooks closer to the user than the standard vertical posts in a power rack assembly.

As shown in FIGS. 1 and 2, the present invention shown generally at 1, the at least one support member 3 is comprised of at least two vertical members or plates that meet at 20 a 90 degree angle to form a right angle. The vertical plate 7 that is most distal to the parallel vertical support post 5 further possesses a cylindrical post 9 that corresponds in size to the aperture in the vertical posts in a power rack assembly. Such cylindrical post 9 fits through such aperture in a vertical post of a power rack assembly to allow the at least one support member 3 to be removably connected to the vertical posts of the power rack assembly as shown in FIGS. 1 and 2. As shown in FIGS. 4, 6 and 8, the cylindrical post 9 may be located near the top of the vertical plate 7. The cylindrical post 9, however, may be located at any point 30 along the length of the vertical plate 7.

As shown in FIGS. 3 and 4, the vertical plate 7 with the cylindrical post 9 is attached to the back surface 11 of a vertical post of the power rack assembly such that the 40 cylindrical post 9 is fitted into an aperture of the vertical post. In another embodiment, the vertical plate with the cylindrical post is attached to the front surface of a vertical post of the power rack assembly.

FIGS. 4 and 6 illustrate that the at least one support member 3 is connected to a parallel vertical support post 5 that can receive a support hook for barbells. The parallel vertical support 5 is comprised of a rigid rectilinear hollow structure 13 having equally spaced apart and aligned apertures 15 or through-holes into which barbell support hooks 50 may be adjustably secured. As shown in FIGS. 1, 2, 3, 4, 6 and 7, the at least one support member 3 and parallel vertical support 5 are connected via at least one angled rigid segments 17. The angle rigid segments are connected to the vertical plate 19 that is most proximal to the parallel vertical support 5. The at least one support member 3 and parallel vertical support 5 may be connected via any rigid connector 60 that provides adequate support.

In a preferred embodiment, the present invention is constructed of steel or another metal having adequate strength to withstand the weight of the barbells and weights.

In another embodiment, as shown in FIGS. 9-12, the present invention is comprised of the at least one support

member **3** comprised of at least two vertical member or plates that meet at a 90 degree angle to form a right angle. The vertical plate **7** that is most distal to the parallel vertical support post **5** further possesses a cylindrical post **9** that further possesses at least one circular plate at the distal end of the cylindrical post **9**. Such at least one plate and cylindrical post **9** fits or pops into place in an aperture in a vertical post of a power rack assembly or similar exercise equipment to allow the at least one support member **3** to be removably connected to the vertical posts of the power rack assembly. In such embodiment, the parallel vertical support **5** is comprised of a rigid rectilinear hollow structure **13** having equally spaced apart and aligned slits **15** or slots into which barbell support hooks may be adjustably secured.

The foregoing detailed description is given for clearness of understanding only, and no unnecessary limitations should be understood therefrom, as modifications will be obvious to those skilled in the art.

I hereby claim:

1. An exercise equipment attachment comprised of at least one support member that removably attaches to a vertical post in an exercise equipment wherein said at least one support member is fixed to a parallel vertical support member possessing equally spaced apart and aligned apertures that can receive a support hook for barbells wherein the at

least one support member is comprised of at least two vertical members that meet at a 90 degree angle to form a right angle and wherein one vertical member possesses a first solid surface having a cylindrical post extending from the first solid surface and a second solid surface oriented facing away from the cylindrical post wherein the cylindrical post corresponds in size to fit within an aperture in the vertical post in a power rack assembly.

2. An exercise equipment attachment according to claim **1** wherein the cylindrical post possesses at least one circular plate at one end of the cylindrical post that corresponds in size to fit within an aperture in the vertical post in a power rack assembly.

3. An exercise equipment attachment according to claim **1** wherein the parallel vertical support member is comprised of a rigid rectilinear hollow structure.

4. An exercise equipment attachment according to claim **3** wherein the parallel vertical support member possesses equally spaced apart and aligned apertures into which barbell support hooks may be adjustably secured.

5. An exercise equipment attachment according to claim **3** wherein the parallel vertical support member possesses equally spaced apart and aligned slots into which barbell support hooks may be adjustably secured.
